CLAIM

The ornamental design for a volatile material dispenser, as shown and described.

DESCRIPTION

FIG. 1 is an isometric view of a top, front, and right side of an ornamental design for a volatile material dispenser; FIG. 2 is a front elevational view of the volatile material dispenser of FIG. 1;

FIG. 3 is a rear elevational view of the volatile material dispenser of FIG. 1;

FIG. 4 is a right side elevational view of the volatile material dispenser of FIG. 1;

FIG. 5 is a left side elevational view of the volatile material dispenser of FIG. 1; and,

FIG. 6 is a top plan view of the volatile material dispenser of FIG. 1.

The broken lines are included for the purpose of illustrating portions that form no part of the claimed design.
